DESIGN FOR A SPREAD OR SIMILAR ARTICLE

Charles S. Jacobs, New York, N. Y.

Application March 16, 1937, Serial No. 68,200

Term of patent 3½ years

To all whom it may concern:

Be it known that I, Charles S. Jacobs, a citizen of the United States of America and a resident of New York city, county of Bronx, State of New York, have invented a new, original, and ornamental Design for a Spread or Similar Article, of which the following is a specification, reference being had to the accompanying drawing forming a part thereof, in which

Fig. 1 is a plan of one corner of a chenille spread showing my new design;

Fig. 2 is a section thereof through the line 2—2 of Fig. 1;

Fig. 3 is a reduced plan view of the spread showing my design in its entirety.

I claim:

The ornamental design for a spread or similar article, as shown.

CHARLES S. JACOBS.
